UNITED STATES PATENT OFFICE

163,263

HOLDER FOR HEXAGONAL WRENCHES

Charles E. Dodd and Lino Scusa, Phoenix, N. Y.

Application August 3, 1949, Serial No. 4,266

Term of patent 14 years

(Cl. D54—13)

To all whom it may concern:

Be it known that we, Charles E. Dodd, a citizen of the United States of America, and a resident of Phoenix, in the County of Oswego and State of New York, and Lino Scusa, a citizen of the United States of America, and a resident of Phoenix, in the county of Oswego and State of New York, have invented a new, original, and ornamental Design for a Holder for Hexagonal Wrenches, of which the following is a specification, reference being had to the accompanying drawing, forming part thereof.

In the drawing:

Figure 1 is a front elevational view of a wrench holder showing our new design;

Figure 2 is a perspective view;

Figure 3 is a rear elevational view thereof; and Figure 4 is a bottom plan thereof.

The wrenches shown in broken lines are for illustrative purposes only.

We claim:

The ornamental design for a holder for hexagonal wrenches, substantially as shown and described.

CHARLES E. DODD.
LINO SCUSA.
